UNITED STATES PATENT OFFICE.

JAMES DUVALL, OF CAMAS, WASHINGTON.

PAPER-BAG-MAKING MACHINE.

1,325,466.

Specification of Letters Patent. Patented Dec. 16, 1919.

Application filed July 8, 1915. Serial No. 38,768.

To all whom it may concern:

Be it known that I, JAMES DUVALL, a citizen of the United States, and a resident of Camas, county of Clark, State of Washington, have invented a new and useful Improvement in Paper-Bag-Making Machines, of which the following is a specification.

My invention relates to paper bag-making machines, and particularly to the tube-forming part.

In the pre-existing machine, the devices performing the step of forming the continuous strip of paper into the tube from which the bag is later made, have a tendency to tear the paper strip in said operation, and in so doing frequently necessitated the stopping of the machine, which causes a loss of time and diminishes the output of the machine.

20 The details of my invention are herein-after described, with reference to the accompanying drawings, in which:

Figure 1 is a side elevation of the left-hand portion of my machine commonly known as the former section; in broken lines is shown the course taken by the paper strip in its passage through this portion of the machine.

Fig. 2 is a plan view of the parts shown in Fig. 1.

Fig. 3 is a vertical transverse section taken approximately on the line 13—13 of Fig. 2. The broken lines of this figure show the paper tubing and partially formed tucks therein.

Fig. 4 is a view similar to Fig. 3 taken on the line 14—14 of Fig. 2.

Fig. 5 is a further similar section taken on the line 15—15 of Fig. 2.

40 Fig. 5^a is a vertical section taken approximately on the line 5^a—5^a of Fig. 2.

Fig. 6 is a diagrammatic view showing the location and operation of the lip and slitter knives; Figs. 7 to 12 inclusive are details of construction.

In order to more readily describe my devices, I shall make use of certain trade terms well known to anyone versed in the art of paper-bag making. The paper is delivered to the machine in sheet form, and my device operates to transform the plain sheet into a continuous tube provided with a longitudinal tuck in each side.

55 The section of the machine in which this transformation is accomplished will hereafter be referred to as the "former" section,

and the tucked paper tubing will be referred to as the "tube." In this former section, is located the stamper which makes an imprint on the sheet at such intervals that each finished bag will bear an individual stamp. The lip-knife and slitter knives are also located in this section and perform their functions in a manner similar to that of the stamper.

The former comprises two standards, *a*, (see Figs. 1 and 2) mounted on the table *b* of the machine. At the top of the standards is rigidly supported a bearing box *c* (see Fig. 5^a), in the ends of which are inserted plugs *d*, in which is journaled the shaft *e*. An opening *f* is cut in the face of the box *c*. The base of the box *c* has pendent arms *g* and *h* connected by a web *i* at the top and the lowermost ends of the pendent arms and have integral flanges *j* to which the lower former plate 56 is attached.

The pendent arm *g* is made with a groove *k*, and the lowermost end of this arm is made with forwardly projecting tongue *l*. At the lower end of the arm *h* is an inclined flange *m* to which the front folder plate *n* is attached. To the arm *h* is fastened a bracket *o*, having a stud *r* on which is journaled, the female die holder *p*, see Figs. 5^a and 6, to the curved base of which is fastened the female die *s* (see Fig. 7). Said die is a thin flat piece of metal, having in it an opening conforming with the knife *t*, see Figs. 6, 7 and 8.

90 The front folder plate *n* is shaped as an isosceles trapezoid having its smaller base coincident with the lower edge of the flange *m*. Rigidly attached to the shaft *e* (see Fig. 5^a) is a lever arm *u*, said arm extending through the opening *f* in the box *c*, this opening being of sufficient size to allow a partial revolution of the arm on the shaft *e*. A link *v* connects the lever arm *u* with the lever arm *q*, such link moving in a recess 100 *k* of the pendent arm *g*.

Rotatably journaled in the standards *a*, below and in direct vertical alinement with the axis of the bearing box *c*, is a shaft 2 commonly referred to as the slitter lip knife 105 shaft. At the far end of the shaft *e*, is a rigidly fixed lever arm *w* connecting with a link *x*. The lower end of this link is made with a slot *y* in which bears the slitter lip knife shaft 2 and the lowermost end of the link bears a cam roller *z*. On the far end of the shaft 2 is rigidly fixed a cam 3, in the

groove of which bears the cam roller α . The rotation of the shaft 2 will give the link w a reciprocating motion, thereby throwing the lever w up and down, and giving a similar movement to the lever arm u , thereby actuating the link v . In this way the die holder p will be given a swinging motion about its fulcrum r .

Rotated by the slitter lip knife shaft 2 and 10 moving in the same plane of action as the female die mouth are the slitter knives 4 and the lip knife t . (See Figs. 6 and 12). The slitter knives holder 5 carrying a cross arm 6, which has one side longer than the other, is 15 rigidly fixed on the shaft 2. The slitter knives 4 are adjustably attached to the ends of the cross arm 6 by means of set-screws 8 bearing in slots 7.

The lip knife holder 9 is rigidly fixed on 20 the shaft 2 adjacent the slitter knives holder 5. This holder, however, is set a little ahead of the slitter holder. In this way the lip knife t and the slitter knives 4 will not be in alinement, but the former will always be 25 slightly in advance of the latter. That part of the lip knife holder to which the lip knife is attached, projects outwardly to one side as shown in Fig. 9, thereby locating the lip knife midway between the slitter knives and 30 in the same vertical plane as the lip knife holder.

On the shaft 2, is a rigid gear 10 through which motion is transmitted to this shaft. In the standards a below the slitter lip knife 35 mechanism is journaled a driven shaft 11 on which is mounted a gear 10', and a stamper arm 13, carrying an adjustable stamper 13' the head of which is curved.

A shaft 14, is rotatably journaled in the 40 standards a and carries a paper compression-roll 15 and a spur-gear 16, the latter meshing with the spur-gear 10' on the shaft 11.

The stamper 13 imprints the paper running 45 over the paper compression-roll 15.

In bushings 17 of the standards a is journaled the ink-fountain shaft 18, carrying a spur gear 19, which meshes with an intermediate gear 34. An ink-fountain drum 21 50 which has as an integral part of it a vibrating cam 20, is also rigidly mounted on the shaft 18, (see Fig. 5^a.)

Bolted to the base is a cam roll bracket 32, having on its upper end the cam roller 33, 55 bearing in the groove of the vibrating cam 20, (see Fig. 5^a). This cam action imparts the vibrating motion to the ink-fountain shaft and all of its attachments.

A bracket 36, having an inclined slot 37, 60 in which a freely running composition roll 38 is loosely journaled, is bolted to the base b . This composition roll bears against the ink-fountain drum 21 and is frictionally driven by it. The inclined slot 37 permits a 65 limited movement of the composition roll, so

that when the ink pump valve 26 comes to that part of its revolution where it contacts with the composition roll, the latter will be moved slightly in its slot. Such contact transfers a quantity of ink from the ink 70 pump to the composition roll, and the vibrating motion of the ink fountain causes this ink to be distributed uniformly over the composition roll.

During each revolution of the stamper 75 13', it contacts once with the composition roll 38, thereby taking the ink from the latter and holding it ready to make an imprint upon the paper. Two paper rolls 39 and 40 (see Fig. 1) are loosely journaled in the 80 lower portions of the standards a . On the upper parts of said standards are mounted brackets 41, in rearmost ends of which is loosely journaled a freely running paper roll 42. On the lower ends of the standards a , 85 are mounted brackets 43, which support the paste pan holder 44 and its necessary attachments. The paste pan 45 sets in this holder and a plate 46 fastened to the paste pan holder 44 holds the pan in position. A 90 paste bottle 48, is held by the uprights 49, in the pan 45 in such way that the level in the pan remains constant. Arms 50 support a loosely running past-wheel, 51 the latter running in the slot 47, (see Fig. 2) of the 95 plate 46, and having its bottom portion continually immersed in the paste.

To the pendent arm g of the bearing box e , is rigidly attached a former support 52. See Figs. 2, 3, 4, 5, and 5^a. This support 100 has a horizontal base and an inclined upper face, and its end abutting against the pendent arm g is made with a groove to fit the tongue l , and the parts are connected by screws 55; see Fig. 5^a.

To the base of the former support 52 and the flanges j , is fastened the lower former-plate 56; (see Figs. 1, 2 and 5^a). This plate is considerably wider than the former support, as shown in Figs. 3, 4, and 5, extends 110 from lowermost edge of the folder plate n through the former section. Openings in this plate are provided for the lip knife and slitter knives respectively. The upper former plate 57 is screwed to the upper face 115 of the former support said plate being also wider than the former support, but toward its receiving end it is tapered as shown at 58, Fig. 2.

Posts 59 spaced at equal distances from 120 the center line of the machine are set upright in the base b . Cross pieces 60 connect the opposite posts, being rigidly secured to same by the studs 61.

On the cross pieces 60, are secured stringers 62, (see Fig. 2) by bolts 63. These stringers extend longitudinally, converging slightly and support the former wheel. On these stringers, opposite each other, at intervals, lateral slots are provided, in which are 130

adjustably supported the former wheel posts 65, which provide a bearing upon which the former wheels rotate. The former wheels 66 serve to start the tucks in the 5 paper tubing. The former wheels 67, 68 and 69 are placed on the remaining posts in their order respectively, and form a graduation conforming with the inclination of the upper former plate 57, (see Figs. 3, 4 and 5).
 10 The former wheels 67 are shaped somewhat like a grooved pulley having dissimilar flanges. The upper flanges 70 extend out over the upper former plate 57 and the lower flanges 71 extend into the channels 15 formed by the two former plates and their support. See Fig. 3.

The former wheels 68 are somewhat similar in construction to the former wheels 67, the only difference being that the heights 20 and slopes of their flanges are varied so as to conform with the new cross section of the former support and its attached plates. See Fig. 4.

The former wheels 69 are circular wheels, 25 similar to the wheels 66, and rotate in the channel between the upper and lower former- plates in the same manner as the lower flanges of the wheels 67 and 68. Besides making the tucks and shaping the paper to 30 the tubing form, these wheels serve also as roller bearings for the paper as it is drawn forward to the draw roll section. These parts heretofore mentioned, with the exception of the shaft by means of which motion 35 is transmitted to the parts of this section, constitute the entire former section.

Two parallel standards 72 are mounted on the base *b*, (see Fig. 1) and are provided with brackets 73, in which is journaled a 40 guide-roll 74. Two draw rolls 76, 81 in vertical alinement with each other are journaled in the standards 72.

In the standards 72 is also journaled the carrying drive-shaft (not shown). Each 45 extremity of which carries a disk 110, from which disks extend connecting rods 111 to the carriages (not shown) for reciprocating the latter.

On the base *b* is a journal post 114 sup- 50 porting one end of a shaft 119 on which is a gear 120. The journal post is made with a journal bracket 115, carrying a shaft on which is mounted a gear (not shown) meshing with the gear 120; the latter gear con- 55 stituting a part of the train transmitting motion from the prime mover-shaft to the various devices of the former section. The motion transmitting devices are arranged as convenient.

60 I shall now trace the passage of the paper through the former section.

In Fig. 1, the paper sheet *a'* is shown at its initial point running over the paper roll

40. From here it runs over the paper roll 39, and the paste wheel 51 contacting with 65 said paper leaves a continuous line of paste near one edge of the sheet.

Next the paper passes over the compres- 50 sion roll 15, and receives the imprint of the stamper. From this roll the sheet *a'* 70 runs up over the paper roll 42. As the paper leaves the latter roll, the two edges *b'* are drawn over the front folder plate *n*, 75 toward each other, while the inner part *b'* of the sheet is drawn under the plate *n*. These edges are pushed toward each other as shown in Figs. 3, 4, and 5, and the tucks 80 in the sides of the tube are made by the former wheels acting in conjunction with the stationary former plates. The starting 85 of this tuck is shown at *c'* in Fig. 1. While the tubing is being drawn over the lower former plate, the slitters and lip-knives cut the slit and tongue at pre-determined intervals. As the tubing is drawn into the 90 draw roll section, it is first pasted down by the draw rolls, so as to make a finished tube.

I claim:

1. In a machine of the character de- 90 scribed, the combination with means for feeding forward a continuous strip of material, longitudinally extending flat mem- 95 bers located one above the other but spaced apart, and forwardly converging, a series of former elements located at both sides of the upper of said members, and having relative motion with respect to the latter, such former elements having V-shaped portions over-lying both faces of the sides of the upper of said members, and horizontal disks interposed between the forward ends of said members.

2. In a machine of the character de- 105 scribed, the combination with means for feeding forward a continuous strip of material, longitudinally extending flat mem- 110 bers located one above the other but spaced apart, and forwardly converging, a series of former wheels journaled at both sides of the upper of said members, each of said wheels being made with V-shaped peripheral groove, the opposite faces of which, in the successive units of the series are brought nearer together, progressively; the grooved 115 portions of said wheels over-lying both faces of the sides of the upper of said members, and rotatable horizontal disks interposed between the forward ends of said members.

3. In a machine of the character de- 120 scribed, the combination with means for feeding forward a continuous strip of material, longitudinally extending flat mem- 125 bers located one above the other but spaced apart, and forwardly converging, a series of

former wheels journaled at both sides of the upper of said members, each of said wheels being made with V-shaped peripheral groove, the opposite faces of which, in the successive units of the series are brought nearer together, progressively; the grooved portions of said wheels over-lying both faces of the sides of the upper of said members, the upper portion of said peripheral groove having a conical flare, and projecting beyond the lower portion of said peripheral groove, and horizontal disks interposed between the forward ends of said members.

15 4. In a machine of the character described, the combination with means for feeding forward a continuous strip of material, longitudinally extending flat members located one above the other but spaced apart, and forwardly converging, the receiving end of the upper of said members being tapered, a series of former wheels journaled at both sides of the upper of said members, each of said wheels being made with

20 V-shaped peripheral groove, the opposite faces of which, in the successive units of the series are brought nearer together, progressively; the grooved portions of said wheels over-lying both faces of the sides of the upper of said members, the upper portion of said peripheral groove having a conical flare, and projecting beyond the lower portion of said peripheral groove.

25 5. In a machine of the character described, the combination with means for feeding forward a continuous strip of material, longitudinally extending flat members located one above the other but spaced apart, and forwardly converging, and a series of former wheels journaled at both sides of the upper of said surfaces, each of said wheels being made with V-shaped peripheral groove, the opposite faces of which, in the successive units of the series are brought nearer together, progressively; the grooved portions of said wheels over-lying both

30 35

faces of the sides of the upper of said members.

6. In a machine of the character described, the combination with means for feeding forward a continuous strip of material, longitudinally extending flat members located one above the other but spaced apart, and forwardly converging, a series of former wheels journaled at both sides of the upper of said surfaces, each of said wheels being made with V-shaped peripheral groove, the opposite faces of which, in the successive units of the series are brought nearer together, progressively; the grooved portions of said wheels over-lying both faces of the sides of the upper of said members, and the upper portion of said peripheral groove having a conical flare, and projecting beyond the lower portion of said peripheral groove.

7. In the machine of the character described, in combination with means for feeding forward a continuous strip of material, a former element comprising longitudinally extending upper and lower members, spaced apart, and forwardly converging, and other former elements located on both sides of said longitudinal members having relative motion with respect to the latter, and being provided with grooved portions overlying the edges of the upper of said longitudinal members.

8. In the machine of the character described, in combination with means for feeding forward a continuous strip of material, a former element comprising longitudinally extending upper and lower members, spaced apart, and forwardly converging, means for guiding said strip to, and bringing the side portions thereof over the sides of the former element, and other former elements located on both sides of said longitudinal members, having relative motion with respect to the latter, and being provided with grooved portions overlying the edges of the upper of said longitudinal members.

JAMES DUVALL.
